LAMP

Hilyard R. Robinson, Washington, D. C., and Aksel
J. C. Knudstrup, Vienna, Va.

Application October 28, 1937, Serial No. 171,584

3 Claims. (Cl. 240—81)

This invention relates to lamps and more particularly to a lamp which is adapted to provide diffused light which may be reflected either upwardly or downwardly or both.

- 5 Another object of this invention is to provide in a lamp structure for providing diffused light, means for adjustably supporting the reflectors so that the light rays may be directed or spread to the desired degree.
- 10 Another object of this invention is to provide a lamp structure which may be used as a floor or table lamp wherein the light bulbs are substantially concealed in reflectors which may be adjusted relative to the light bulbs so as to control the diffusion of the light rays.

A further object of this invention is to provide in a light structure for this kind means for cooling the reflectors positioned about the light bulbs.

- 20 A still further object of this invention is to provide an improved means for supporting a portion of the indirect light reflector so that light rays may be projected upwardly and downwardly from between this portion of the inverted reflector.
- 25 Still another object of this invention is to provide in a light or lamp structure, a plurality of annular louvers and supporting means therefor so as to prevent glare from the reflector from a position laterally therefrom in addition to confining the light rays in a particular field.

To the above ends essentially and to others which may hereinafter appear, the invention consists of the novel construction, combination and arrangement of parts as will be more specifically referred to and illustrated in the accompanying drawing wherein are shown several embodiments of the invention, but it is to be understood that changes, variations and modifications may be resorted to which fall within the scope 40 of the invention as claimed.

In the drawing:

Figure 1 is a vertical section partly broken away and in section of a lamp structure constructed according to an embodiment of this invention,

Figure 2 is an enlarged fragmentary vertical section of the upper or indirect reflector disposed on top of the lamp,

50 Figure 3 is a fragmentary view in elevation showing the manner of securing the louver supporting means to the upper reflector,

Figure 4 is a fragmentary vertical section of a modified form of switch structure for the several 55 light bulbs, and

Figure 5 is a fragmentary top plan of the device.

Referring to the drawing the numeral 10 designates generally a standard which is provided with a base structure 11 at the lower end thereof. This standard 10 is of tubular construction and is mounted in an annular flange 13 provided in the upper portion of the base 11. The base 11 comprises a plate 12 to which is secured as by a bolt 14, a second or lower plate 15. The lower plate 15 carries a plurality of feet 16 which include cushioning members 17. A hollow body 18 is disposed above the base plate 12 and is provided with an annular outer portion 19 terminating in a dependent flange 20 which engages about 15 the two plate members 12 and 15.

A lower reflector 21 provided with an annular lower flange 22 is supported on a cylindrical supporting member 23 carried by a sleeve 24. The supporting member 23 engages about the flange 20 25 and contacts with a shoulder 25 provided between the lower end of the reflector 21 and the annular flange 22. The supporting member 23 is connected to the sleeve 24 by means of an annular flange 26 and a plurality of vents 27 are 30 provided through this flange 26 to permit air to enter the cylindrical supporting member 23 and rise upwardly into the reflector 21. The sleeve 24 is adjustably secured along the length of the tubular standard 10 by means of set screws 30 35 or the like. The standard 10 is provided at a point below the upper end thereof with an annular rib or bead 29 which limits the downward movement of the shield supporting sleeve 24. An upper rib 30 is provided adjacent the upper end 35 of the standard 10 and this rib 30 limits the upward movement of the sleeve 24.

A lamp socket supporting member 31 is secured to the upper end of the tubular standard 10 and a pair of lamp sockets 32 are secured to the 40 supporting member 31 in substantially upwardly divergent relation and light bulbs 33 engage the sockets 32 within the reflector 21. A tubular conduit 34 is disposed concentrically of the standard 10 and extends downwardly through an opening 35 provided in the hollow base member 18 and is connected to the base structure by a connector 36 of a type commonly called "Hickey" which includes a pair of threaded sleeve members 37 disposed in spaced apart relation and 45 connected together by means of arcuate arms 38. In this manner the electric wires may be extended through the hollow base 11 into the lower end of the conduit 34 and then brought upwardly 50 through a similar connector 39 which is secured 55 through a similar connector 39 which is secured

to the upper end of the conduit 34. The lamp sockets 32 may be connected to the electric wires through the upper connector 39. A relatively short conduit or nipple 40 is threadably secured 5 at its lower end to the support 31 and to the connector 39. The nipple 40 at its upper end has a socket 41 threadably secured thereto in which a light bulb 42 is mounted.

An inverted reflector generally designated as 10 43 is disposed above the reflector 21 and comprises a substantially conoidal-shaped inner portion 44 which is connected at its outer portion to a downwardly extending frusto-conical shield portion 45 terminating in a rib or bead 46 at the 15 lower end thereof. The reflector 43 is provided at its inner portion with a sleeve 47 engaging in a socket or annular supporting member 48 carried by a cylindrical member 49. The cylindrical member 49 is disposed about the socket 41 and 20 is provided at its lower end with an inverted frusto-conical portion 50 having holes 51 therethrough so that air rising upwardly in the reflector 21 may pass upwardly through the cylindrical member 49 and about the socket 41. The cylindrical supporting member 49 is secured at its 25 lower end to a nut 52 which is threaded onto the nipple 40. The nut 52 is provided with a reduced upper portion 53 providing a shoulder or seat against which the lower end of the supporting 30 member 49—50 engages. The lower end of the supporting member 49—50 is detachably secured to the nut 52 by means of a set screw 54.

An upper reflector 55 is disposed above the reflector 43 being secured thereto in upwardly 35 spaced relation by means of a plurality of bracket members 56. The reflector 55 comprises an inner reflector member 57 and an outer reflector member 58 which is formed by turning over or reverting the material of which the reflector 57 40 is constructed and then extending the material downwardly at its upper portion as at 59 to provide a substantially cylindrical portion 59 and the lower end of the cylindrical portion 59 is secured to the upper end of a frusto-conical portion 60. 45 The lower end of the frusto-conical portion 60 terminates in a dependent flange 61 which is spaced from the upper end or wall of the frusto-conical shield portion 45. The inner reflector 57 is provided with a plurality of circumferentially 50 arranged button hole slots 62 in which a plurality of louver supporting bolts 63 engage. A plurality of annular or cylindrical louvers 64 are mounted on the supporting bolts 63 and are disposed in concentric relation being concentric to the reflector 57 and the center of the standard 55 10.

The base structure 11 as shown in Figure 1 is provided with a pair of switch members 65 and 66 which are disposed on the annular portion 60 19 and are adapted to be connected to the wires or conductors leading to the light bulbs 33 and 42. Preferably these switch members 65 and 66 are of a type which will permit the lighting of the light bulbs in either reflector 21 or 55 or both or 65 if desired any one or more of the light bulbs in the lower reflector 21.

In Figure 4 there is shown a slightly modified form of this light structure wherein the supporting sleeve 23^a is provided with a plurality of switch members 65^a and 66^a. This structure may be used where the standard 10^a is constructed as part of a floor lamp or the like. In this form the lower inverted shield or reflector 21^a is similar in every detail to the reflector 21 and light bulbs and sockets similar to the light bulbs and

sockets shown in Figure 1 are positioned internally of the reflector 21^a.

In the use of this lamp structure the light bulbs 33 and 42 are adapted to be connected to a suitable source of current supply and a selected one 5 or both of the switches 65 and 66 may be closed to light up the desired light bulbs. The upper reflector structure 43 may be initially adjusted by rotation of the supporting nut 52 so as to adjust the reflector 43 relative to the light bulbs 33 and 10 also relative to the light bulb 42. The desired spread of light rays may be provided by vertical adjustment of the inverted reflector 21. This adjustment is made by means of the set screws 28.

When the light bulb 42 is lighted the rays therefrom will be projected upwardly by the reflecting upper side of the reflector portion 44 and by means of the inner reflector 57. In addition thereto certain light rays will pass between the lower end of the reflector 57 and the upper side 20 of the reflector 44 and then out through the space 67 between the reflector 55 and the reflector 43. The annular louvers 64 may be readily removed for replacement of the light bulb 42 by unthreading the lock nuts 68 which are 25 threadably mounted on the bolts 63 and engage on opposite sides of each button hole slot 62. By providing a space between the upper reflector 55 and the reflector 43, the heat from the light bulb 42 may be readily dissipated in addition to providing means for the passing of certain light rays outwardly and downwardly about the exterior of the reflector 43.

What is claimed is:

1. In a lamp structure including a base, a 35 standard secured to and extending upwardly of said base, a plurality of socket members, means securing said socket members to the upper portion of said standard, an inverted reflector above said socket members, means supporting said reflector from the upper end of said standard, a second reflector opposed to said first reflector and disposed thereabove, means engaging said standard and said second reflector for supporting said second reflector, a socket member disposed concentrically of said second reflector for supporting a light bulb above said second reflector, said second reflector having a substantially cone shaped reflecting upper surface, a third reflector disposed above said second reflector, bracket 45 means supporting said third reflector above said second reflector, an outwardly flared apron integral with said third reflector and extending outwardly and downwardly thereof, a plurality of 50 annular louvers disposed concentrically of said third reflector, bolts secured to said louvers, said third reflector having a plurality of circumferentially arranged button hole slots to receive said bolts for detachably supporting said louvers.

2. In a lamp structure including a base, a 60 standard secured to and extending upwardly of said base, a plurality of socket members, means securing said socket members to the upper portion of said standard, an inverted reflector about said socket members, means supporting said reflector from the upper end of said standard, a second reflector opposed to said first reflector and disposed thereabove, means engaging said standard and said second reflector for supporting said second reflector, a socket member disposed concentrically of said second reflector for supporting a light bulb above said second reflector, said means including a threaded coupling whereby said second reflector may be vertically adjusted relative to said socket member therefor, said 70 75

second reflector having a substantially cone shaped reflecting upper surface, a third reflector disposed above said second reflector, bracket means supporting said third reflector above said 5 second reflector, an outwardly flared apron integral with said third reflector and extending outwardly and downwardly thereof, a plurality of annular louvers disposed concentrically of said third reflector, bolts secured to said louvers, said 10 third reflector having a plurality of circumferentially arranged button hole slots to receive said bolts for detachably supporting said louvers.

3. In a lamp structure including a base, a standard secured to and extending upwardly of 15 said base, a plurality of socket members, means securing said socket members to the upper portion of said standard, an inverted reflector about said socket members, means slidable on said standard supporting said reflector on said stand- 20 ard, means holding said slidable means in adjusted position, a second reflector opposed to

said first reflector and disposed thereabove, means engaging said standard and said second reflector for supporting said second reflector, a socket member disposed concentrically of said second reflector for supporting a light bulb above 5 said second reflector, said second reflector having a substantially cone shaped reflecting upper surface, a third reflector disposed above said second reflector, bracket means supporting said third reflector above said second reflector, an 10 outwardly flared apron integral with said third reflector and extending outwardly and downwardly thereof, a plurality of annular louvers disposed concentrically of said third reflector, bolts secured to said louvers, said third reflector having a plurality of circumferentially arranged button hole slots to receive said bolts for detachably supporting said louvers.
